The ornamental design for a dual ID card display armband, as shown and described.

DESCRIPTION

FIG. 1 is a perspective view of a dual ID card display armband, showing the new design in a closed position;
FIG. 2 is a front elevational view of FIG. 1;
FIG. 3 is a rear elevational view of FIG. 1;
FIG. 4 is a right-side elevational view of FIG. 1;
FIG. 5 is a left-side elevational view of FIG. 1;
FIG. 6 is a top plan view of FIG. 1;
FIG. 7 is a bottom plan view of FIG. 1;
FIG. 8 is a front elevational view thereof, illustrated in an open position;
FIG. 9 is a rear elevational view of FIG. 8;
FIG. 10 is a right-side elevational view of FIG. 8;
FIG. 11 is a left-side elevational view of FIG. 8;
FIG. 12 is a bottom plan view of FIG. 8; and,
FIG. 13 is a top plan view of FIG. 8.

The broken lines showing a person in FIG. 1, ID cards in FIGS. 1 and 2, and credit cards in FIG. 8 depict environmental matter while the invention is in use, and form no part of the claimed design. The remaining broken lines represent stitching, and are part of the claimed design.
